UNITED STATES PATENT OFFICE.

OLIN H. BASQUIN, OF CHICAGO, ILLINOIS, ASSIGNOR TO THE LUXFER PRISM PATENTS COMPANY, OF SAME PLACE.

DESIGN FOR A PRISM-PLATE.

SPECIFICATION forming part of Design No. 27,344, dated July 13, 1897.

Application filed June 15, 1897. Serial No. 640,918. Term of patent 14 years.

To all whom it may concern:

Be it known that I, OLIN H. BASQUIN, a citizen of the United States, residing at Chicago, in the county of Cook and State of Illinois, 5 have invented and produced a certain new and useful Design for Prism-Plates, of which the following is a description.

My invention relates to a design for a prism-plate, and is illustrated in the accompanying 10 drawing, wherein the figure is a view of a prism-plate of my design.

The plate is composed of a series of prism-lights A A, each hexagonal in form and having each a circular body of prisms B B thereon, 15 leaving a smooth surface at the corners of the

hexagons. Between the several prism-lights are frame-pieces C C.

The essential features of the design consist in a prism-plate composed of a series of prism-lights, each light hexagonal in form and each 20 light having a body of prisms thereon, substantially circular, and interposed frame-pieces.

I claim—

The design for a prism-plate substantially 25 as shown and described.

OLIN H. BASQUIN.
